UNITED STATES PATENT OFFICE.

MARTIN N. NOLING, OF ROCKFORD, ILLINOIS, ASSIGNOR TO BARBER-COLMAN COMPANY, OF ROCKFORD, ILLINOIS, A CORPORATION OF ILLINOIS.

YARN CLEARER.

Application filed December 31, 1923. Serial No. 683,571.

The invention pertains to yarn clearers for winders or spoolers such as are employed in textile mills, and the general object of the invention is to provide a device of this character which is capable of effectually clearing the thread or yarn of gouts, particles of fibre, leaf, and other extraneous matter.

A further and more specific object is to provide a yarn clearer which is readily adjustable so as to be capable of operating upon yarns of varying sizes; which is highly sensitive; and which is operable automatically to break the thread in the event an enlargement or foreign particle thereon attempts to pass through the device.

In the accompanying drawings I have illustrated a preferred embodiment of my invention, but it is to be understood that the invention is not limited to the particular construction and arrangement of parts illustrated and hereinafter described, for it is contemplated that various changes may be made therein by those skilled in the art without departing from the spirit and scope of the invention as expressed in the appended claims.

Figure 1 of the drawings is a fragmentary front elevational view of a device embodying my invention.

Fig. 2 is an end view thereof.

Fig. 3 is a view taken in the plane of line 3—3 of Fig. 1.

Fig. 4 is a fragmentary horizontal section taken in the plane of line 4—4 of Fig. 1.

Fig. 5 is a fragmentary perspective view showing the construction of the yarn clearing members or plates.

Figs. 6 and 7 are perspective views showing details of construction.

Fig. 8 is a fragmentary vertical sectional view taken in the plane of line 8—8 of Fig. 4.

Fig. 9 is a similar view, but showing the parts in a different operative relation.

My improved yarn clearer is adapted for use with various forms of spoolers and winders, but is especially adapted for use in connection with an automatic winder of the type disclosed in the Colman Patents Nos. 1,267,977 and 1,274,386 granted May 28, 1918 and August 6, 1918, respectively. In said patents there is shown a winder equipped with bobbin holders of the side

delivery type wherein the bobbin is revolved as the yarn is unwound. Said winder is also provided with a cam bar which is arranged to operate upon the clearing device in a manner which will hereinafter appear.

My improved yarn clearer when constructed in accordance with the present disclosure, comprises a pair of overlapping members or plates providing opposed parallel surfaces between which the thread to be cleared is passed, in combination with means for positioning the thread between said surfaces, and a controlling mechanism for the plates adapted to vary the distance between said surfaces. Two plate members providing the opposed parallel surfaces are designated respectively 10 and 11 in the drawings (Figs. 5 and 8). These members are mounted so as to be swingable on horizontal axes and are adapted to slide relative to each other in such swinging movement. The member 10 is mounted to turn on a tubular member 12 which is mounted in a pair of spaced parallel vertical standards 13 (Fig. 4). The member 11 is journaled upon a pin 14 arranged eccentrically with respect to a shaft 15 which in turn is journaled in the tube 12. It will be observed that the plates 10 and 11 are thus mounted to swing on parallel axes spaced a short distance apart. For holding the two plate members in sliding relation one of the members (herein the member 10) is provided at opposite edges with hooked flanges 16 forming ways in which the opposite edges of the other plate member are adapted to slide. The respective members are preferably formed of sheet metal and their rear edges are bent upon themselves to form bearings 10^a and 11^a (Fig. 8) adapted to receive respectively the tube 12 and the pin 14. To permit the member 11 to be mounted within the tube 12, the latter is cut away upon its forward side as shown at 17 (Fig. 8), and the bearing portion 10^a of the member 10 is slotted longitudinally at its forward side, as shown at 18.

The member 11 in the present instance projects beyond the forward edge of the member 10 a substantial distance, and adjacent the forward edge of said member 10 is provided with a slot 19 open at one end. The forward wall 20 of this slot constitutes

one of the two opposed parallel surfaces of the clearing device, the other one of said surfaces being formed by the forward edge 21 of the member 10. If desired, the pin 14 5 may be in the form of a screw (Fig. 6) threaded into an opening located eccentrically in the end of the shaft 15. The screw has a head 22 at its outer or free end to retain the bearing member 11^a in position.

10 The means for guiding the thread *a* into position between the opposed surfaces 20 and 21 of the clearing members may be of any suitable character. Herein it comprises a pair of vertically spaced plates 23 and 24 15 secured upon the upper and lower sides respectively of a block 25. These plates are extended beyond the right hand end of the block to form guide members 26 and 27. The upper one of these members 26 has a 20 curved guiding surface 28 (Fig. 1), and the lower one of the members has a forwardly opening slot 29 the rear end wall of which provides a guiding surface 30. The rear edge of the upper member 26 on the other 25 hand, provides an opposed guiding surface 31 (see Fig. 3). It will be seen by reference to Fig. 4 that a thread entering the slot 29 will be guided rearwardly around the member 26 by the curved surface 28, when 30 it will spring into position between the opposed surfaces 30 and 31. Preferably the forward end of the member 11 is shaped like the guide member 26 to provide a rearwardly curving guide surface 32 which assists in positioning the thread between the 35 opposed surfaces 20—21 of the clearing device. As shown clearly in Figs. 4 and 5, the rear wall of the slot 19 is longer than the forward wall thereof, thus providing a portion 32^a which serves as a stop to limit rearward movement of the thread when the latter is moving laterally into place in the slot 19. The member 11 has at its forward edge 40 a depending stop member 33 which is adapted to engage with the upper surface of the plate 23 so as to hold the members 10 and 11 in approximately horizontal position with the opposed surfaces 20, 21 separated.

45 The upright standards 13 in which is mounted the tube 12 may be integrally connected at their lower ends to form a U-shaped frame which is mounted upon a base composed of the plates 23 and 24 and their spacing block 25, the frame being secured to the base as by means of a screw 34. This frame in addition to providing a support for the tube 12 carries a plurality of fingers 35 which constitute a grid against which the thread is pressed by means of one 50 or more detector fingers 36 suitably mounted upon the winder.

To adjust the plate members 10 and 11, in order properly to space the surfaces 20, 21 apart in accordance with the size of yarn 55 being wound, it is only necessary to turn the

shaft 15 which effects a relative sliding movement between the plates. To enable the shaft 15 thus to be turned I provide at one end (Fig. 4) a forwardly extending portion or crank arm 37 which is held by means of a coiled torsion spring 38 downwardly upon an adjustable stop screw 39 carried by the aforesaid base of the device. One end of said spring 38 engages with one of the standards 13 of the frame and the other end engages with the crank arm as shown clearly in Figs. 1 and 4.

60 As aforesaid, the plate members 10 and 11 of the clearing device are held in approximately horizontal position by means of the stop member 33 resting upon the upper surface of the plate 23, and it will be apparent that upon rotation of the shaft 15 in a counterclockwise direction (Fig. 5), the plate member 11 will be drawn rearwardly by reason of its eccentric mounting upon the shaft, relative to the member 10. The result is a lessening of the distance between the opposed guiding surfaces 20 and 21. Conversely, a reverse rotation of the shaft 15 65 tends to increase the distance between the opposed surfaces 20, 21. Preferably the plate 11 is downwardly offset at the slot 19 so as to position the surface 20 opposite the surface 21 in the plate 10; and to enable the said surfaces to be drawn together, the forward edge of the plate 10 is beveled as shown at 40 to receive the downwardly inclined portion formed by the offset at the end of the slot 19 in the plate 11.

70 Normally the surfaces 20, 21 are spaced apart a distance sufficient only to permit the thread to pass therebetween without contact of the body of the thread with the surfaces 20, 21, any particles of foreign matter upon the thread being cleared therefrom by engagement with the plate members 10 and 11 at their respective surfaces 20 and 21. But it sometimes happens that an irremovable enlargement or the like on the thread (see Fig. 9) may attempt to pass through the clearer, in which event, the engagement of the enlargement with the relatively light plates 10 and 11 will carry them upwardly 75 into the position shown in Fig. 9. In such movement of the plates, due to their eccentric mounting, the opposed surfaces 20, 21 move together and clamp the thread, causing it to break under the tension due to rotation of the yarn mass being formed.

80 As hereinbefore stated, the winder tender mechanism is equipped with a cam bar arranged to engage the crank arm 37 of the clearing device in the travel of said mechanism so as to turn the shaft 15 in a clockwise direction, thus holding the opposed surfaces 20, 21 apart so that the device can readily be cleaned by a blast of air from the tender mechanism. Obviously when the device is used on a non-automatic winder or

spooler, the crank arm may be lifted manually to allow the accumulated clearings to drop out and facilitate the cleaning operation.

In the following claims the terms "yarn" and "thread" are intended to include any analogous material.

I claim as my invention:

1. A yarn clearer comprising a pair of plates providing a pair of opposed clearing edges and mounted for relative sliding movement to decrease the distance between said edges upon engagement of said edges by a gout on the thread, whereby to clamp and break the thread, and means for guiding a thread into position between said edges.

2. A yarn clearer comprising a pair of plates providing a pair of opposed edges and mounted for relative sliding movement to vary the distance between said edges, said plates being mounted for pivotal movement upon the engagement of an obstruction on the thread with the plates, and said edges being movable toward each other in such pivotal movement of the plates whereby to clamp and break the thread.

3. A yarn clearing device having, in combination, a pair of plates pivotally mounted on spaced parallel axes and adapted to slide relative to each other, said plates providing opposed surfaces between which a thread is adapted to pass, and means for adjusting the axes of said plates whereby to move them relative to each other and vary the distance between said opposed surfaces.

4. A yarn clearing device having, in combination, a pair of plates pivotally mounted on spaced parallel axes and adapted to slide relative to each other, said plates providing opposed surfaces between which a thread is adapted to pass, and means for adjusting the axes of said plates whereby to move them relative to each other and vary the distance between said opposed surfaces, the pivotal mounting of the plates being such that when they are swung in one direction said opposed surfaces move into engagement with the thread to clamp it.

5. A yarn clearing device comprising a pair of plates mounted for relative sliding movement, a pivotal support for one of said plates, the other one of said plates being pivotally mounted eccentrically of said support, the respective plates providing opposed surfaces between which a thread is adapted to pass, and means for adjusting said supports relative to each other whereby to vary the positions of the respective plates and hence the distance between said surfaces.

6. The combination of a plate member, a pivotal support for said member comprising a stationary tube, a second plate member pivoted eccentrically within said tube, said plate members providing opposed surfaces between which a thread is adapted to pass, and means for adjusting said pivotal sup-

ports relative to each other whereby to vary the distance between said opposed surfaces.

7. A yarn clearer comprising, in combination, a pair of members providing a pair of opposed surfaces adapted to receive between them a thread to be cleared, and means for pivotally supporting said members whereby they are capable of moving with the travelling thread upon the engagement of an enlargement thereon, and said members being adapted in such movement to slide relative to each other and into engagement with the thread to clamp it.

8. The combination of a pair of plate members mounted in parallel axes, means for adjusting said axes relative to each other whereby to effect relative movement between said members in parallel planes, and means providing a pair of opposed surfaces on the respective members movable toward or away from each other in their said movement.

9. A yarn clearing device comprising, in combination, a plate member mounted to turn on a horizontal axis, a second plate member mounted to turn on an axis spaced a short distance below the axis of the first plate member, means for supporting said plate members for relative movement in approximately horizontal planes, and means providing on the respective plate members a pair of opposed surfaces between which a thread being wound is arranged to pass, said surfaces being movable toward and away from each other in the swinging movements of said plate members.

10. A yarn clearer comprising, in combination with a base, a frame on said base, a tubular member journaled in said frame, a shaft journaled in said tubular member, a pair of plate members mounted respectively upon said shaft and tubular member and adapted to move relative to each other in a relative rotation between the shaft and said tubular member, said plate members providing a pair of opposed surfaces between which a thread being wound is arranged to pass.

11. A yarn clearer comprising, in combination with a base, a frame on said base, a tubular member journaled in said frame, a shaft journaled in said member, a pair of plate members mounted respectively upon said shaft and tubular member and adapted to move relative to each other during a relative rotation between the shaft and said tubular member, said plate members providing a pair of opposed surfaces between which a thread being wound is arranged to pass, and means carried by the base for guiding a thread into position between said surfaces.

12. A yarn clearer comprising, in combination with a base, a frame on said base, a tubular member journaled in said frame, a shaft journaled in said tubular member, a pair of plate members mounted respectively

upon said shaft and tubular member and adapted to slide relative to each other, said plate members providing a pair of opposed surfaces between which a thread being wound is arranged to pass, means for supporting the plate members in a normally horizontal position, and means for effecting relative movement between said tubular member and shaft whereby to adjust the plate members to vary the distance between said opposed surfaces.

13. A yarn clearer comprising, in combination with a base, a frame on said base, a tubular member journaled in said frame, a shaft journaled in said member, a pair of plate members mounted respectively upon said shaft and tubular member and adapted to slide relative to each other, said plate members providing a pair of opposed surfaces between which a thread being wound is arranged to pass, means for supporting the plate members in a normally horizontal position, and means for adjusting the plate members to vary the distance between said opposed surfaces comprising a crank arm on said shaft, an adjustable stop with which said arm is adapted to engage, and spring means tending to hold said crank arm against said stop.

14. A yarn clearer comprising, in combination, a pair of plate members mounted for relative movement and providing a pair of opposed surfaces between which a thread is

arranged to pass, pivotal supports for the respective plate members arranged eccentrically with respect to each other and adapted to vary the distance between said surfaces, one of said supports comprising a shaft having a crank arm, a stop with which said arm is adapted to engage, and spring means for holding said crank arm against said stop.

15. A yarn clearer for clearing yarn running in a generally vertical direction, comprising, in combination, two members pivoted on parallel horizontal axes, means for normally supporting one of said members in approximately horizontal position, the other member being supported upon the first mentioned member, said members when in normal position providing between them a space for the passage of the thread to be cleared, which space is reduced when the plates are pivotally raised by engagement with a gout on the thread.

16. A yarn clearer comprising, in combination, two members pivoted on parallel axes, one of said members being supported upon the other, said members when in normal position providing between them a space for the passage of the thread to be cleared and being pivotally movable to reduce said space when the plates are engaged by a gout on the thread.

In testimony whereof, I have hereunto affixed my signature.

MARTIN N. NOLING.
